United States Patent Office

Des. 212,802
Patented Nov. 26, 1968

212,802

BENCH

John S. Terket, 135 N. Parkside Ave.,
Chicago, Ill. 60644

Filed July 27, 1967, Ser. No. 8,034

Term of patent 14 years

(Cl. D15—11)

FIG. 4.

FIG. 1 is a perspective view of a bench, showing my new design;

FIG. 2 is a top plan view of said bench;

FIG. 3 is an elevational view of one side thereof; and

FIG. 4 is an elevational view of the rear of said bench.

I claim:

The ornamental design for a bench, substantially as shown.
